DESIGN FOR A COMBINATION CRAVAT AND PENCIL HOLDER

Joseph O. Pollack, Chicago, Ill.

Application August 12, 1935, Serial No. 58,083

Term of patent 7 years

To all whom it may concern:

Be it known that I, Joseph O. Pollack, a citizen of the United States, residing at Chicago, in the county of Cook and State of Illinois, have invented a new, original, and ornamental Design for Combination Cravat and Pencil Holders, of which the following is a specification, reference being had to the accompanying drawing, forming a part thereof.

Fig. 1 is a plan view of the combination cravat and pencil holder showing the rotatable member for holding a pencil in the back of the article;

Fig. 2 is a front elevational view of the article

showing the pencil holder extending transversely to the cravat holder;

Fig. 3 is a view of the right end of the article as shown in Fig. 1; and

Fig. 4 is a rear view of the device showing the pencil holder shifted to a position wherein a pencil contained therein would extend parallel to the cravat holder.

I claim:

The ornamental design for a combination cravat and pencil holder as shown and described.

JOSEPH O. POLLACK.
